LEVER-RETARDING ACCESSORY FOR DENTAL ENGINE

John M. Clauser and Frederick K. Clauser, St. Louis, Mo., assignors to Midvale Dental Supply Company, St. Louis, Mo., a corporation of Missouri

Application May 10, 1954, Serial No. 428,458

6 Claims. (Cl. 201—48)

This invention relates in general to controllers for dental engines and, more particularly, to a lever-retarding accessory therefor. The invention is particularly adapted for engines operated at the relatively high speeds of 12,000 R. P. M. which is a recent development in dental practice.

Dental engines for operating discs and burrs are usually driven by electric motors which have associated therewith a speed controller normally located on the floor and including a horizontally movable lever having a pedal portion at each of its ends for operation by the user's foot. Connected to the lever is a control arm for progressive movement across a series or shunt resistance, fixed contacts arranged concentrically of the controller for increasing or decreasing the engine speed. Contacts on one side of the median line of the controller cause rotation of the motor in one direction while the contacts on the other side of said line will effect rotation in the opposite or reverse direction. The lever is biased into "off" position by return springs, so that upon release of the lever from any one of its circuit-closing positions, the same will be automatically swung to move the control arm to circuit-open position.

On release of the lever from high speed position, wherein the shunt resistance is open, it will rapidly accelerate under influence of the springs with the interval of travel from such position to "off" position being relatively short. It has been noted that during such interval, a well-developed sparking takes place between the commutator and brushes. Such sparking is intense enough to cause pitting of the commutator and a burning of the brushes which materially decrease engine effectiveness, requiring periodic replacement of parts. If the movement of the lever from high speed to "off" position be retarded sufficiently, sparking between the commutator and brushes is reduced to non-damaging proportions.

Assumedly, the destructive sparking is due to self-inductive flow of current which occurs across the brushes; also, the short-circuiting action of the brushes on the coils brought out to the commutator segments; also, the electro-motive force generated by the armature under its own momentum after the circuit is opened.

If the control lever moves slowly enough towards "off" position, the effects noted above are decreased to an extent that the destructive sparking is avoided.

The main object of the present invention is to slow the return of the control lever upon the operator's release of the pedal and avoid the rapid action otherwise resulting from the force of the return springs.

Another object is to provide an accessory for ready application to a common form of pedal and lever of a dental engine controller for slowing down the action of the lever-return-spring and activated by the speed of the lever.

Another object is to utilize the inertia of a weight applied to the control lever to obtain the slowing down effect.

2

Another object is to provide an accessory for application to a controller lever and pedal which will provide frictional resistance to the action of the lever-return-spring in order that the lever may move more slowly from high speed to "off" position.

Another object is to provide an accessory of the character stated which can be cheaply manufactured; which may be installed upon the lever by unskilled individuals; which may be adapted for use with various types of lever 10 pedal formations; and which is reliable and durable in usage.

These and other detailed objects are obtained by the structure illustrated in the accompanying drawing, in which:

15 Figure 1 is a perspective view of a dental engine and its mounting and an associated foot-actuated controller to which the invention may be applied.

Figure 2 is a fragmentary side view of the controller provided with a lever retarding accessory embodying the 20 present invention.

Figure 3 is a fragmentary top plan view of the accessory shown in Figure 2, and related controller mechanism.

Figure 4 is a perspective view of another form of lever-retarding accessory constructed in accordance with the 25 present invention.

Figure 5 is a fragmentary side view of a controller lever and pedal provided with an accessory of the form shown in Figure 4.

30 The dental engine 1 is mounted on a supporting yoke 2 attached to a standard 3. Operatively connected to engine 1 by leads 4 extending through standard 3 is a conventional type foot controller having a cylindrical casing 5 with arcuate openings 6 in the sides thereof through which extends a horizontally movable lever 7 pivoted at P and enlarged at its ends to form pedals 8. Movement of the lever by either pedal in clockwise or 35 anti-clockwise direction shifts a well-known rheostat device to start and accelerate the motor step by step according to the positions determined by the operator. Such movement elongates one of springs S and when the pedal is moved to return the lever to normal "off" position, the spring ordinarily would accelerate the lever movement to such extent as to result in undesirable 40 sparking.

To avoid this result, there is mounted upon each pedal 8 a lever-retarding accessory comprising a pair of parallel side plates 9, 10 at opposite sides of pedal 8 and spaced apart by rivets 11 and sleeves 12 above and below the 45 pedal. Plate 9 has an extension 13 projecting across and above lever 7 with its lower edge resting on the upper face of the lever, spaced from the inner end of pedal 8. Extension 13 terminates in a flange 14 turned inwardly toward controller casing 5, parallel to plates 9, 10. Mounted upon flange 14 by pivot pin 15 is a normally vertically disposed rocker arm 16 projecting in its lower portion downwardly beyond lever 7 and having its lower end weighted, as at 17. The upper portion of rocker arm 16 forms a clevis 18 opening toward controller casing 5 for 50 supporting a rotatable pin 19 which mounts a friction wheel 20 of rubber or similar material. Friction wheel 20 will normally be in immediate proximity, but out of contact with, controller casing 5.

When the operator releases foot pressure on pedal 8 and lever 7 and a spring S rotates the lever from high speed position to "off" position, the lower weighted end of rocker arm 16 will swing outwardly through centrifugal force as the lever is accelerated, causing wheel 20 to frictionally engage controller casing 5, as indicated in dotted lines in Figure 2. The braking action so produced partially counteracts the force of the return spring, whereon 55 60 65 70

a retarding or snubbing action is brought about which inhibits the expected acceleration of lever 7 and causes the control arm to move more slowly across successive contacts toward circuit-open position than if the spring action were not resisted. When the return of lever 7 is thus retarded, minimum or no sparking action occurs between the engine commutator and brushes since the motor decelerates more slowly, thereby prolonging the life of the commutator and brushes.

In Figure 4 another form of lever-retarding weight is shown which comprises a unitary, elongated, U-shaped body, having a weight of about one pound, and preferably having parallel side walls 21, 22, and arcuate top wall 23, and being cut away in its lower portion at its normally inner end to provide a shoulder 24. Walls 21, 22 are spaced apart a distance substantially equal to the thickness of pedal 8 and may be pressed towards each other to be secured to the lever. Shoulder 24 will overlie lever 7, which is of greater width than the thickness of lever 8, as shown at 7' in Figure 3.

Upon release of lever 7 from foot pressure, the inertia or weight will resist the force of the lever-return springs so that lever 7 will be slowly returned to "off" position, as the spring overcomes the inertia of the weighted pedal. With this type of retarding or snubbing device, the control arm on lever 7 will move more slowly as the lever returns to "off" position, whereby sparking is effectively reduced or eliminated between the commutator and brushes. An additional advantage is that the deceleration of the motor avoids the likelihood of the motor belt jumping from its pulleys to the annoyance and interruption of the operator.

The lever-retarding accessory of the present invention can be readily applied to the pedal of any type of controller, irrespective of design of such pedal. No modification or alteration of the pedal is required to properly apply the accessory thereto and it is apparent that the same may be mounted without the exercise of skill on the part of the user. The accessory is so constructed as to be securely engaged upon the lever pedal so that inadvertent displacement is avoided.

The details of construction may be varied otherwise than as indicated without departing from the spirit of the invention and the exclusive use of those modifications coming within the scope of the claims is contemplated.

What is claimed is:

1. In combination with a dental engine motor controller, including a housing having a side wall provided with an elongated slot, there being a rheostat lever projecting through said slot and terminating in a pedal for engagement by an operator and provided with a spring for moving the lever to a normal "off" position, a weight device readily applicable to said pedal and movable therewith and operated automatically upon release of the operator's thrust on said pedal to retard, by its inertia, the speed of the return movement of said lever and controller throughout the extent of the return movement.

2. For use with a dental engine controller having a

spring-biased operating lever with a pedal formed at its end, an accessory for said pedal to resist the force of the lever spring comprising a body for application upon the pedal, and a friction element rockably carried on said body for movement toward said controller through centrifugal force on spring-actuated swinging of said lever to engage said controller for retarding swinging of said lever.

3. For use with a dental engine controller having a spring-biased operating lever with a pedal formed at its end, an accessory for said pedal to resist the force of the lever spring comprising a body for application upon the pedal, and an arm rockably carried on said body at the inner end thereof, said arm being of increased weight at its lower end, and a friction element carried at the upper end of said arm for engagement with the controller on rocking of the arm through centrifugal force.

4. For use with a dental engine controller having a spring-biased operating lever with a pedal formed at its end, an accessory for said pedal to resist the force of the lever spring comprising a body for application upon the pedal, and an arm rockably carried on said body at the inner end thereof, said arm being weighted a predetermined amount at its lower end, a yieldable friction element carried at the upper end of said arm in confronting relation to said controller for engagement therewith on rocking of the arm through centrifugal force.

5. In combination with a dental engine having a motor and a rheostat type control including a horizontally disposed radial lever pivoted near one end and movable under thrust by an operator, applied to its other end, from an off position to successively higher-speed operative positions, there being a spring returning said lever to off position when released from said thrust, a weight detachably mounted on said lever near its outer end and forming an inertia device resisting acceleration in the return movement of the released lever to off position by said spring.

6. In combination with a dental engine motor controller, including a housing having a side wall provided with an elongated slot, there being a rheostat lever projecting through said slot and terminating in a horizontally movable pedal for lateral thrust by an operator and provided with a spring for returning the lever to a normal "off" position, a separately formed weight device readily applicable to said pedal and movable therewith and acting automatically, by its inertia, upon release of the operator's thrust on said pedal to retard the spring-induced return movement of said lever until the lever reaches its normal "off" position.
